A. P. WINIARSKI

SCRUBBING AND CLEANING IMPLEMENT

Filed July 30, 1924

UNITED STATES PATENT OFFICE.

ADAM P. WINIARSKI, OF NEW YORK, N. Y.

SCRUBBING AND CLEANING IMPLEMENT.

Application filed July 30, 1924. Serial No. 729,013.

To all whom it may concern:

Be it known that I, ADAM P. WINIARSKI, a citizen of the United States, residing at New York city, county of New York, and 5 State of New York, have invented certain new and useful Improvements in Scrubbing and Cleaning Implements, of which the following is a specification.

This invention relates to improvements 10 in cleaning implements and has particular reference to a combined scrubbing, cleaning and scraping device employed for cleaning floors, walls, windows and the like.

Scrubbing brushes as ordinarily used are 15 gripped by the hand and applied to a floor by the user while supported on the hands and knees thereby causing considerable strain and effort. While the user is working in such strained and awkward position, 20 water and soap are applied to the floor and after the dirt has been loosened by the action of the scrubbing brush, the dirty water is repeatedly taken up and rinsed in a pail of water which must be frequently renewed 25 with added effort and expenditure of time.

Efforts have been made to use a scrubbing brush by means of a long handle attached thereto but even when so used it has been necessary to clean up the area gone over by 30 the brush and furthermore the handle soon becomes loose from the head of the brush.

It has also been the practice to employ 35 scrubbing brushes with long handles and to attach to the brush some form of cleaning or scraping device which is usually connected to the brush in such manner that it cannot be readily removed.

An object of the present invention is to 40 provide an improved implement in which a long handle is securely maintained in connection with the top of the implement and wherein said body is constructed to permit of the ready attachment and detachment of a cleaning and scraping device thereto.

Another object is the provision of an 45 implement of the above character which is simple in construction, easy to manufacture, and effective in carrying out the purposes for which it is designed.

The above and other objects will appear 50 more clearly from the following detail description when taken in connection with the accompanying drawing which illustrates a preferred embodiment of the inventive idea.

In the drawing:

Figure 1 is a fragmentary side elevation 55 of the implement partly broken away and shown in section, the parts being arranged as when the brush of the implement is in use.

Figure 2 is a fragmentary side elevation 60 of the implement showing the parts in position when the cleaning device is being used.

Figure 3 is a fragmentary front elevation 65 of the implement, partly broken away and shown in section.

Figure 4 is a similar view in top plan; and

Figure 5 is a perspective view of the cleaning and scraping device removed from the body of the implement.

In the form illustrated in the drawing, 70 the invention is shown as comprising a body 6, preferably made of wood and of substantial rectangular formation. To the bottom face of this body, which forms a supporting block, there is attached a scrubbing brush 7 preferably secured to the body 6 by means of screws 8 or other suitable fasteners which 75 will permit of the removal of said brush from the body when the brush becomes worn so that the same may be replaced by a new brush.

The body 6 is provided, preferably in 80 proximity to the center thereof, with an inclined opening 9 extending therethrough from the upper to the lower surface and capable of receiving an end of the handle 10 which may be of any desired length. 85 The end of the handle projecting into said body is beveled as indicated at 11 and is engageable with the surface of the brush 7 in contact with the under surface of the body 6. When so constructed and arranged, 90 the end of the handle 10 frictionally contacts the wall of the opening 9 and by forming the end of said handle with a bevel it will be apparent that said handle will be securely maintained in position in the body 100 and prevented from turning therein.

The body 6 is further provided, preferably in its front face, with a recess or channel 12 extending longitudinally of said body throughout its entire length, the major or inner portion of said recess being preferably arcuate in cross section. The recess 105 12 communicates with the front face of the

body 6 through the restricted portion 13 of said recess. This recess 12 is capable of receiving a cleaning and scraping device consisting of a rigid handle portion 14 shaped to conform to the contour of the recess 12 and made of a diameter which will permit said handle portion to fit snugly in said recess and at the same time permit of its removal from the body whenever desired at which time said portion 14 may be securely grasped in the hand. This handle portion 14 is provided with the reduced extension or shank 15 which is capable of engagement in the reduced portion 13 of the recess when the handle portion 14 is mounted in the body. The shank 15 is formed with a longitudinally extending groove 16 in which is mounted one edge of a flexible member 17, generally known as a squeegee, secured in position in said groove by means of suitable fasteners such as screws 18. The device is mounted in the body 6 by inserting one end of the handle portion 14 into one end of the recess and then sliding the device longitudinally in said recess until the ends of the handle portion are flush with the ends of the body. One end of the handle portion 14 has secured thereto and projecting beyond its periphery a scraping member 19 which may be employed when the device is removed from the body and utilized as a window cleaner during which use the

handle portion 14 is grasped by the operator in the usual manner. This member 19 also forms a stop which will abut against the adjacent face of the body 6 to limit the movement of the handle portion 14 in the recess 13 when said handle portion is being mounted in the body. Thus the cleaning and scraping device may either be used as shown in Figure 2 or the same may be removed from the body and employed as a separate implement, as when cleaning windows.

What is claimed is:

An implement of the class described including a body having a recess extending longitudinally therethrough, said recess having an enlarged portion and a restricted portion communicating with one face of said body, a cleaning and scraping device having a portion serving as a rigid handle of a diameter to be securely grasped in the hand to permit of the device being used separately from said body, said handle portion corresponding in shape to that of said recess and engageable in said recess, and said device having a movement longitudinally of said recess to permit of the same being detached from said body.

In testimony whereof I have affixed my signature.

ADAM P. WINIARSKI.
